Patented July 19, 1921.

INVENTOR

BY Daniel W. Schenck
Arthur C. Draw.
ATTORNEY

UNITED STATES PATENT OFFICE.

DANIEL W. SCHENCK, OF KANSAS CITY, KANSAS.

BROOM.

1,385,152.

Specification of Letters Patent. Patented July 19, 1921.

Application filed October 18, 1919. Serial No. 331,616.

To all whom it may concern:

Be it known that I, DANIEL W. SCHENCK, a citizen of the United States, residing at Kansas City, in the county of Wyandotte 5 and State of Kansas, have invented certain new and useful improvements in Brooms; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to broom heads and particularly to a device adapted to receive a broom straw or brush unit in such manner that it can be readily removed for the introduction of a new broom unit when the 20 previously introduced one becomes worn.

I have provided a simple, durable and efficient, as well as inexpensively constructed, broom head which will be practically indestructible, and I contemplate providing 25 broom units of broom straw or brush which can be made up ready for insertion into the head and carried by the dealer so that the purchaser need only obtain a new unit in order to restore the broom to its original 30 condition.

I have also provided a broom head which can be manipulated in a convenient manner without the use of special tools.

In order to illustrate the generic principle of my invention, reference should be 35 had to the accompanying drawings, it being understood, however, that changes in form, proportion and minor details of construction may be resorted to without departing from 40 the spirit of the invention or sacrificing any of its advantages.

Figure I is a perspective view of a complete broom, constructed in accordance with my invention.

45 Fig. II is a perspective view of the broom head opened up, showing the broom unit removed therefrom.

Fig. III is a cross sectional view through the broom, and

50 Fig. IV is a bottom view of the head.

Referring now to the drawings by numerals of reference:

1 designates a broom head which is constructed in the form of a receiving member 55 or socket of inherent, resilient material so

that the jaws 2 and 3 will inherently spring apart, as indicated in Fig. II. The jaws 2 and 3 are provided with inturned flanges 4 and 5, which are notched or slit, as at 6 and 7 respectively, so that the jaws may 60 readily flex when released by the clamping screw or bolt 8. The jaw 2 is provided with bosses 9 and 10, having elongated slots 11 and 12 and the jaw 3 is provided with bosses 13 and 14 having openings 15 and 16 65 to receive the bolts 8 and 8'. The openings 15 and 16 may be threaded to receive the threaded ends of the bolts 8 and 8' and, if desired, locking nuts 17 may be employed on the ends thereof.

The lower ends of the jaws 2 and 3 are provided with inturned flanges 18 and 19, which are adapted to engage with the sides of the broom unit 20, shown as consisting of longitudinally arranged fibers or strands 75 secured together in proper form by one or more lines of stitching 21 in the usual manner of sewing brooms.

The upper end of the head is provided with a threaded neck 22 into which may 80 be screwed the broom handle 23, the handle being preferably secured against displacement by a transverse bolt 24, passing through the head and secured in place by a fastening device shown as a nut 25.

When the parts are in the position shown in Fig. II, the broom unit may be introduced into the jaws and the bolts caused to enter the openings 15 and 16, whereupon the jaws may be drawn together either by screwing 90 the bolts into the bosses 13 and 14 or by the nuts 17, and drawing the jaws together will cause the flanges 18 and 19 to tightly engage against the sides of the broom unit and hold it securely in place. When the 95 broom unit becomes worn, it will be only necessary to release the bolts, take out the old unit and introduce the new one, and since it is proposed to make up these units ready for sale, it will be obvious that a 100 complete broom may be made up in an expeditious manner.

By reference to Fig. II, it will be observed that the slots 11 and 12 are elongated. This is to permit the jaws to readily spring apart 105 when the bolts are released.

In actual practice the members 2 and 3 may be struck up from sheet metal and screwed or otherwise secured together along the seam 26.

What I claim and desire to secure by Letters-Patent is:

1. In a broom head, a hollow member having a handle-receiving neck, the lower end 5 of the member being slitted to provide flexible jaws, inturned, spaced flange members along the ends of the flexible jaws, movable apart when the jaws are expanded and movable together when the jaws are in clamping 10 position, and means for drawing the flexible jaws together.
2. In a broom head, a hollow member having a handle-receiving neck, the lower end of the member being slitted to provide flexible jaws, inturned, spaced flexible members 15 along the ends of the respective jaws to close the spaces between said jaws, the spaced

flange members being movable apart when the jaws are expanded and movable together when the jaws are in clamping position, inwardly projecting teeth on the lower ends of the jaws, and means for drawing the flexible jaws together. 20

3. In a broom head, a hollow member having a handle-receiving neck, the lower end 25 of the broom member being slitted to provide flexible jaws, inturned, spaced flange members along the ends of the respective jaws to close the space between the jaws, means for drawing the jaws together into 30 clamping position, and a handle-engaging bolt passing transversely through the head.

In testimony whereof I affix my signature.
DANIEL W. SCHENCK.
